FORMATION PACKER

Walter T. Wells, Glendale, Calif.

Application June 24, 1932. Serial No. 619,097

8 Claims. (Cl. 166—10)

The present invention is an improved formation packer and relates to that type of well equipment wherein expansible sleeve packing members are carried on a tubular support lowered 5 into a well bore and adapted to be expanded by the weight of the tubing string from which the device is suspended, for the purpose of sealing the space between the tubing and the surrounding formation wall.

10 The objects of the invention include: The provision, in a packer of the character described, of a passage within the packing elements which will facilitate displacement therethrough of fluid which in deep wells is often of a density sufficient 15 to impede or retard movement, in or out, of the packer;

The provision of means for automatically 20 equalizing hydrostatic pressure on the inner and outer surfaces of said packing elements, thereby allowing said elements to deform in a manner 25 normal to their predetermined shape when under compression; the provision of automatic means, responsive to longitudinal movement of the packer, for opening and closing the by-pass therethrough.

Attention is called to my co-pending application for a casing packer, filed June 1, 1932, Serial Number 614,731.

The present invention, while in several respects 30 similar in function to the structure therein described, is better adapted for use in drilled holes before casing is set and is of such slender structure that it is particularly serviceable in bores of 35 small diameter.

Referring to the drawing Figure 1 is a vertical 40 central cross-sectional view of my packer, showing the parts as they would appear in the "run-in" position.

Figure 2 is a similar view showing the packer 45 set.

Figures 3, 4, 5, and 6, are cross sections of Figure 1 taken, respectively on the lines III, IV, V, and VI, of said figure.

Figures 7 and 8 are, respectively, front and 45 edge elevations of a rod member.

Figure 9 is a fragmentary sectional view showing 50 alternate restraining means, yieldable and resilient, for maintaining a by-pass through the packer in open position.

Figure 10 is a fragmentary view showing an alternate form of valve and shows automatic 55 means for keeping said valve closed while the packer is being run in.

Referring to the drawing, the numeral 1 indicates a tubular support member exteriorly

threaded at each end as indicated at 2 and 3. The upper end threads 2 are engaged by a collar 4 and a packing nut 6 adapted to compress therebetween backing rings 7, adapted to slidably seal space between tube 1 and a surrounding sleeve member 8.

Sleeve 8 is tapered at the top as indicated in Figure 2 and interiorly threaded to receive a tubing string 9 from which the packer is suspended. The bore of sleeve 8 is reduced as indicated at 10 to form a shoulder 11, said reduced bore being of a size to provide an annular passage 12 between said sleeve and the outer wall of tube 1.

Communicating with passage 12 are quadrilaterally disposed ports 13, bored obliquely downward through sleeve 8.

The lower end of sleeve 8 is provided with an annular groove 14 for engaging the tapered end of a cylindrical expansive packing member 16 which is held in place in any suitable manner, such as by pins 17.

Any desired number of these packing members may be employed. I have elected to show two in the drawing in order to illustrate the manner of their connections, one with the other if more than one is used.

A collar 18 is provided with annular grooves 19 to receive the adjacent ends of the packing sleeves 16 and said collar is bored to form a passage 21, similar to passage 12, between said collar and tube 1.

The lower end of the lowermost of the packing members 16 is engaged in an annular groove 22 in the top of a sleeve member 23, the inner bore 90 of which is of the same diameter as that of sleeve 8.

Said bore is enlarged from the bottom of sleeve 23 to form seats 24 and 26 adapted to complement shoulders 27 and 28 on a foot member 29 secured to tube 1 by the threads 3. An anchor tube 31 is threaded into the bottom of foot member 29.

The chain, consisting of packing members 16 and the connectors 19 as well as the sleeve 23, is suspended from the upper sleeve 8 by quadrilaterally disposed rods 32, Figures 7 and 8, each of which is bent at each end at an angle of ninety degrees to form hooks 33, one of which engages shoulder 11 of the sleeve 8 and the other engages an annular groove 34 in sleeve 23.

As the packer is run in the well, the frictional engagement of the packing 7 between tube 1 and sleeve 8 keeps the parts in the relative positions shown in Figure 2, the rods 32 restraining

the sleeve 23 from closing the lower end of the by-pass within the packing members 16 and around tube 1.

However, when anchor 31 encounters the bottom 5 of the well, weight of the tubing string 9 to which the packer is attached, causes sleeve 8 to move downward with respect to tube 1, as indicated in Figure 2 until seat 24 encounters shoulder 27 on foot member 29, closing the by-pass completely at the bottom.

When this occurs, no further movement downward is possible for sleeve 23, and bars 32 engaged therewith become stationary. The weight of the tubing string is now transmitted to packing members 16 which deform and seal the space between tube 1 and the surrounding surface of the formation as indicated in Figure 2.

The sleeve, descending, moves shoulder 11 away from the hooked portions of rods 32 as indicated in Figure 2.

It is obvious that the rods 32 may be kept in vertical alignment and in proper spaced relation to each other by cutting keyways, not shown in the outer wall of tube 1, and that they may be so positioned as not to obstruct the ports 13.

Operation

When the device is attached to a tubing string 9 as indicated in Figure 2, to be lowered in a well bore the parts are in the relative positions shown in Figure 1. It is essential that the by-pass (12-34) be kept open to decrease fluid resistance. While the packer is being lowered fluid enters said by-pass at the bottom (26) of the sleeve 23 and leaves through ports 13 as indicated by the arrows in Figure 1.

Under ordinary conditions the friction of packing 7 is sufficient to keep the by-pass open.

However, gas conditions may be present which cause occasional surges upward in the bore, which might be of sufficient velocity to thrust foot member 29 upward. I provide both resilient, and positive means, as alternates, shown in Figure 9.

45. Here a spring 37, of the expansion type is interposed between collar 6 and the tapered upper end of the sleeve 8. The thrust of this spring is sufficient to keep the by-pass open.

At 38 I show a shear pin, of soft brass or other 50 suitable metal, extending through the wall of sleeve 8 and threaded into collar 4. This is a positive means for holding the by-pass open, yet it is yieldable to the weight of the tubing string, shearing off under said weight and allowing the closure of the by-pass before the packer is set.

Which ever form is used the operation is the same. The device is lowered till anchor 31 encounters the bottom 36. Thereupon the weight of the tubing string closes the by-pass, sleeve 60 23 moves downward till seat 26 rests on shoulder 27, and the weight of the tubing is applied to the sleeves 16 which deform as shown in Figure 2 closing the surrounding space within the bore.

65. When the packer is withdrawn sleeve 8 moves upward till the hooks 33 on rods 32 are engaged by shoulder 11, whereupon the sleeve 23 is raised and the by-pass opened so that as the packer is withdrawn fluid will enter ports 13 and leave the by-pass through the bottom of sleeve 23.

The purpose of the sleeve valve structure shown is to provide for a limited degree of movement of the anchor 31. Fluid entering the perforations 39 of said anchor 31 might disturb the bottom 70 38 and cause said anchor to settle.

When this occurs the by-pass is closed and remains so till surface 26 clears shoulder 28, even though the face 24 leaves its seat 27.

In Figure 10, I show an alternate automatic means for keeping the by-pass closed while the 80 packer is being run in and open as it is run out.

In this figure the shoulder 28 of Figure 2 is turned off, leaving the area upon which hydrostatic pressure is effective less than that of the similar area of sleeve 23. It results from this structure that, when the packer is lowered, the fluid it encounters will hold sleeve 23 away from foot 29 and keep the by-pass open.

I claim:

1. A formation packer comprising a sleeve member provided at one end with means for engagement with a tubing string and with ports extending through its annular wall, a packing element, of the sleeve type, secured at one end to said sleeve member, a tubular support member extending through said packing member and into said first mentioned sleeve in a manner providing an annular passage between said tube and said sleeves and communicating with said ports, a foot member secured to said tube, a valve sleeve 90 slidable on said tube and connecting with said packing member and provided with surfaces complementary to those of said foot member, whereby said members will co-act to open and close said passage when said valve sleeve is reciprocated.

2. The combination, with the elements set forth in claim 1, of means connecting said first mentioned sleeve with said valve sleeve in a manner resistant to separation thereof but allowing 110 a limited degree of movement, under compression, of said valve sleeve.

3. The combination, with the elements set forth in claim 1, of positive means connecting said first mentioned sleeve with said valve sleeve effective to resist separation thereof but provided with a degree of lost motion permitting compression of said parts when said positive means have been sheared off by compressive force applied to 115 said head and foot members.

4. The combination with the elements set forth in claim 1, of resilient means urging said valve sleeve to its open position.

5. The combination, with the elements set forth in claim 1, of positive means connecting said first mentioned sleeve with said valve sleeve, effective to resist separation thereof, but adapted to yield when compressive force is applied to 125 said members.

6. The combination, with the elements set forth in claim 1, of resilient means, interposed between said first mentioned sleeve and said valve sleeve, effective to resist separation thereof, but adapted to yield when compressive force is applied to 130 said members.

7. The combination, with the elements set forth in claim 1, of frictional means, interposed between said first mentioned sleeve and said valve sleeve, effective to resist separation thereof, but adapted to yield when compressive force is applied to 135 said members.

8. The combination, with the elements set forth in claim 1, of connector members engaging said first mentioned sleeve and said valve sleeve, and means, associated with said connector members, 145 limiting the degree of possible separation of said members but permitting movement thereof, one toward the other.
